SMOKE INSPECTION DEVICE

Robert Hudson Wager, Maplewood, N. J.

Application June 19, 1945, Serial No. 600,366

3 Claims. (Cl. 88—14)

1

The invention relates to smoke inspection devices of the general type shown in my U. S. Patents 1,708,987 of April 16, 1929, and 2,118,716 of May 24, 1938, in which a beam of light is projected horizontally through the smoke leaving a boiler and is reflected within tubing by a plurality of mirrors to an observation unit in the boiler room, the character of the smoke being visible by looking at the reflection on the final mirror included in said observation unit. The smoke reflection on this final mirror has been clearly visible only from one observation station directly in front of the observation unit. It is the object of the present invention, however, to provide an improved observation unit which does not require the fireman to walk periodically to the aforesaid observation station but enables him to also view the smoke reflection equally as well from other points to the right and left of said station, thus permitting him to observe the character of the smoke without interruption to other duties which he may be performing.

Figure 1 of the accompanying drawings is a central vertical longitudinal sectional view through the improved observation unit.

Fig. 2 is a front elevation.

Fig. 3 is an elevation of the plural-plane mirror and its supporting plate, looking in the direction indicated by the arrow 3 of Fig. 1, the mirror holding frame being omitted.

Fig. 4 is a transverse section on line 4—4 of Fig. 3.

Fig. 5 is an end elevation viewed in the direction indicated by the arrow 5 of Fig. 3.

In the drawings above briefly described, the casing of the observation unit is denoted at 6, said casing being in substantially the form of an elbow with an upwardly open light inlet 7 and a flared horizontally open light outlet 8. The upper end of the casing is suitably adapted at 9 for connection with the tubing (not shown) within which the beam of light is downwardly reflected after projection through the smoke leaving the boiler through the usual uptake or breeching.

A plural-plane mirror 10 is mounted in the casing 6 for intercepting the downwardly reflected light beam entering through the inlet 7 and horizontally reflecting said beam through the outlet 8. The mirror 10 comprises a flat inclined central reflecting area 11 and two flat lateral reflecting areas 12, said areas 12 being not only inclined in the same direction as the central area 11 but being transversely inclined at an obtuse angle (preferably about 22½ degrees) to said

2

central area 11. The central area 11 in the present disclosure is substantially triangular and has straight longitudinal edges 13 converging upwardly to a point 14. The lateral areas 12 have straight inner edges 15 extending along the edges 13, and the remaining edges of said areas 11 and 12 are preferably curved to an elliptical outline. The areas 11 and 12, in the present disclosure, are on separate mirror sections 16, 17 and 18 (Fig. 4) but a one-piece mirror could be provided, if desired.

A supporting plate 19 is provided for the mirror sections 16, 17 and 18, said plate being recessed to receive said sections and to also receive an appropriate mirror backing 20. The mirror sections and backing are held in place by a suitable frame 21 secured to the plate 19 by screws or the like 22, this frame being omitted in Figs. 3, 4 and 5.

20 A ball and socket joint 23 is shown for mounting the plate 19 in the casing 6 and permitting pivotal adjustment in various directions. This joint is of the construction shown in the above mentioned patents and includes screws 24 for adjusting, and for locking after adjustment.

25 From the foregoing and the accompanying drawings, it will be seen that novel provision has been made for carrying out the object of the invention. Not only can a visual smoke inspection be made from a central point in front of the casing 6 but from points to the right and left of said central point, with obvious advantages.

While preferences have been disclosed, minor variations may be made within the scope of the 30 invention as claimed.

I claim:

1. In a smoke inspection device, an observation unit comprising a casing having an upwardly open light inlet and a horizontally open light outlet, 35 a plural-plane mirror in said casing for intercepting light rays entering the casing through said inlet and reflecting said rays through said outlet, said mirror comprising a central flat longitudinally inclined reflecting area having right and left longitudinal edges, and two flat longitudinally inclined lateral reflecting areas having inner longitudinal edges extending along said longitudinal edges of said central reflecting area, said two lateral reflecting areas being inclined transversely at an obtuse angle to said central reflecting area, whereby reflected rays will be visible from a central point in front of said light outlet and from points to the right and left of said central point, and means mounting said plural-plane mirror in said casing.

2. In a smoke inspection device, an observation unit comprising a casing having an upwardly open light inlet and a horizontally open light outlet, a plural-plane mirror in said casing for intercepting light rays entering the casing through said inlet and reflecting said rays through said outlet, said mirror comprising a central flat longitudinally inclined reflecting area having right and left longitudinal edges which converge substantially to a point at one end of said central reflecting area, and two flat longitudinally inclined lateral reflecting areas having inner longitudinal edges extending along said longitudinal edges of said central reflecting area, said two lateral reflecting areas being inclined transversely at an obtuse angle to said central reflecting area, whereby reflected rays will be visible from a central point in front of said light outlet and from points to the right and left of said central point, and means mounting said plural-plane mirror in said casing.

3. In a smoke inspection device, an observation unit comprising a casing having an upwardly open

light inlet and a horizontally open light outlet, a plural-plane mirror in said casing for intercepting light rays entering the casing through said inlet and reflecting said rays through said outlet, said mirror comprising a central flat longitudinally inclined reflecting area having right and left longitudinal edges, and two flat longitudinally inclined lateral reflecting areas having inner longitudinal edges extending along said longitudinal edges of said central reflecting area, said two lateral reflecting areas being inclined transversely at an obtuse angle to said central reflecting area, whereby reflected rays will be visible from a central point in front of said light outlet and from points to the right and left of said central point, a supporting plate upon which said mirror is mounted, and a ball and socket joint mounting said supporting plate in said casing for pivotal adjustment, said joint having means for holding said supporting plate against accidental movement.

ROBERT HUDSON WAGER.
